REFRIGERATOR CABINET CONSTRUCTION

Evans T. Morton, Chicago, Ill., assignor to Admiral Corporation, Chicago, Ill., a corporation of Delaware

Application January 2, 1947, Serial No. 719,669

11 Claims. (Cl. 312—214)

1

The present invention relates to a novel refrigerator cabinet construction and particularly to the construction of the front portion of the cabinet involving the doorway frame, the food compartment liners, the outer shell, the sealing of the cabinet against the atmosphere, the securing of the ornamental trim pieces to the cabinet face, the sealing of the space within the door, and the sealing of the door against the doorway frame and the cabinet.

Developments in the mechanical refrigeration art during the past few years have produced on a commercial scale the multi-temperature, multi-compartment refrigerator wherein one of the compartments is cooled to a temperature considerably below the freezing point of water and another of the compartments is cooled to a temperature only slightly above the freezing point of water but with a very high humidity. To give added storage space and cleanliness to these compartments the evaporator coils are secured to the outer surfaces of the compartment liners, the walls of which are cooled to the temperature necessary to produce the desired compartmental temperatures.

Placing the coils exteriorly of the liners places them within the insulated space in the cabinet which is that space between the compartment liner and the outer shell of the cabinet. This space is filled with a heat insulating material such as balsa wool, Aero Felt or rockwool. If there is substantial moisture in this insulated space—and there will be if atmospheric air can leak thereinto—it will condense upon the evaporator coils forming a frost. While it is not necessary to defrost refrigerators of this type as often as the more conventional types of refrigerators, still they must be defrosted at greatly spaced intervals to remove the frost from within the freezing compartment or frost chest which is maintained at the sub-freezing temperature. During the defrosting operation, the frost on that part of the evaporator coil which operates below 32° F. would melt and run into the insulation and the latter would rot or mold and thereby lose much of its insulating qualities; of course, wet insulating material has poor insulating characteristics. Subsequent operation of the refrigerator would freeze the insulation into a solid iced block having poor insulating values. To prevent this condition from arising, it is desirable to seal the insulated space in the cabinet against the ingress of atmospheric air.

Furthermore, sealing the insulated space in the cabinet forms a dead air space therein, the

2

insulating characteristics of which are readily appreciated.

It is, therefore, one of the principal objects of this invention to provide an improved heat insulated refrigerator cabinet wherein the insulated space is sealed against the atmosphere.

Another object is to provide an improved refrigerator cabinet incorporating a one-piece molded plastic doorway frame made of a thermal insulating material which in addition to forming a substantial portion of the front face of the cabinet forms the thermal breaker strip between the atmosphere and the compartments within the cabinet and provides a large portion of the structural support between the food compartment liners and the outer shell.

Another object is to provide an improved refrigerator cabinet wherein the food compartment liners are sealed against the doorway frame in an airtight manner.

Another object is to provide an improved refrigerator cabinet wherein the outer shell is sealed against the doorway frame in an airtight manner.

25 A further object is to provide an improved refrigerator cabinet wherein the food storage compartments and the insulated space are efficiently sealed against the atmosphere and from each other.

Still a further object is to provide an improved refrigerator cabinet for a multi-temperature, multi-compartment refrigerator wherein the compartments are efficiently insulated against heat transfer therebetween through the cabinet door.

30 35 A still further object is to provide a door for a multi-temperature, multi-compartment refrigerator having a gasket engaging the cabinet face to seal one compartment from the other and incorporating means to regulate the pressure of the gasket against the cabinet face.

Another object is to provide a door for a refrigerator having a novel gasket construction to seal the insulated space within the door against the ingress of atmospheric air.

40 45 Another object is to provide a novel means for attaching the ornamental trim to the face of the cabinet.

Still a further object is to provide an improved refrigerator cabinet which may be easily and rapidly assembled and has a rugged construction.

Other objects and advantages will become apparent from the following description taken in conjunction with the accompanying drawings, wherein:

50 Fig. 1 is an elevational view of a multi-tem-

perature, multi-compartment refrigerator with the main outer door removed;

Fig. 2 is an enlarged cross-sectional view taken substantially on the line 2—2 of Fig. 1, looking in the direction of the arrows, and showing a fragment of the door;

Fig. 3 is an enlarged cross-sectional view taken substantially on the line 3—3 of Fig. 1, looking in the direction of the arrows, showing a fragment of the main or outer door but with the inner door removed;

Fig. 4 is an enlarged cross-sectional view taken substantially on the line 4—4 of Fig. 1, looking in the direction of the arrows, showing a section through the main or outer door but with the inner doors removed;

Fig. 5 is a fragmentary cross-sectional view taken in the horizontal plane of Fig. 4 adjacent one edge of the door to show the construction of the inner supports;

Fig. 6 is a sectional view in perspective of the connection between the outer shell and the doorway frame illustrating the means for securing the ornamental trim in place;

Fig. 7 is an enlarged cross-sectional view taken substantially on the line 7—7 of Fig. 1, looking in the direction of the arrows, showing the construction at the lower edge of the doorway frame, with the main outer door eliminated;

Fig. 8 is an enlarged cross-sectional view similar to Fig. 2 illustrating a modified form of door construction; and

Fig. 9 is an enlarged cross-sectional view similar to Figs. 2 and 8 illustrating another modified form of door construction.

The refrigerator cabinet, indicated generally by the reference character 10, includes a doorway frame 12 to which the front edges of the liners forming a freezing locker or frost chest 14 and a moist cold or food storage compartment 16 are secured; a single piece outer shell 18 forming the top and side walls of the cabinet is secured at its front edge to the doorway frame. Below the food storage compartment 16 is a machinery compartment closed by a door 20. The whole cabinet 10 is mounted upon a base frame 22.

The general organization of the refrigerator and a further description of the cabinet forming the present invention are given in the co-pending application of Evans T. Morton, Serial No. 720,080, filed January 3, 1947, for an invention entitled "Refrigerator." In this refrigerator, which is of the multi-temperature, multi-compartment type, the frost chest or freezing compartment 14 is maintained at a temperature of approximately 5° to 8° above zero for the freezing of ice cubes and foodstuffs and for the storage of frozen foodstuffs. This compartment is preferably closed by inner doors 24 which are hinged to the frame 12. (Since these doors do not form any part of the present invention they have been omitted from Figs. 3 and 4 for the purpose of clarity.) The moist cold compartment 16 is maintained at a temperature of about 38° F. with a very high humidity. This compartment is fitted with suitable shelves 26, a tray 28 for storing bulk foodstuffs such as lettuce, tomatoes and the like, and a condensed moisture disposal tray 30. It is insulated from the freezing locker 14 so that the heat transfer therebetween is sufficient to prevent cooling the compartment 16 below freezing. Both the frost chest 14 and the moist cold compartment 16 are pro-

vided with evaporator coils which are secured to the outer surfaces of the inner walls.

The cabinet 10 is provided with a main, outer door 32 having a one piece plastic material inner panel 34 and a metallic outer panel 36, the space between the panels being filled with suitable insulation 38. A sealing gasket 40 is secured to the periphery of the door and engages the front face of the cabinet to seal the food storage compartment 16 and the freezing locker 14 from the atmosphere. The door 32 will be described in greater detail hereinafter.

The doorway frame 12 comprises a pair of generally vertical leg members 42 which are joined by a top cross member 44, a bottom cross member 46 and a medial cross member 48. The members 42, 44, 46 and 48 are formed of a phenolic resin, hard rubber or some other similar, suitable plastic material; the material chosen must be nonhygroscopic, moldable, and a good thermal insulator; the term "molded plastic material" in the claims is meant to include all such materials. The frame 12 is molded in one piece, and its members are formed in cross section to give the desired structural strength and stability while being relatively light in weight, since it is desired that a substantial portion of the load imposed by the food compartment liners be carried by the frame. In some instances the frame would be the sole support for the compartment liners.

The members, 42, 44, 46 and 48 of the frame have a general channel shape with web portions 50 lying in the plane of the front face of the cabinet (Fig. 2). The web 50 adjacent the compartment 16 is formed at its inner edge with an integral rearwardly extending flange 52 which is provided at spaced intervals with a plurality of bosses 54 formed with bores 56. A food compartment liner 58 which defines the food storage compartment 16 is provided at its front with a forwardly facing flange 60 which is bent forwardly at 62. The flange 60 is provided with a plurality of holes 64 coinciding with the openings 56 in the bosses 54. Self-tapping screws 66 are threaded through the holes 64 into the bosses to secure the flange 60 against the rear edge of the flange 52.

A block 68 of insulating material is placed against the inner face of the web 50 and is secured thereto by a layer 70 of a bituminous cement such as Hydrolene or some other adhesive compound. The whole of the joint between the flange 52 and the flange 60 is given a thick coating 72 of Hydrolene or some other suitable material, thereby sealing the joint between the food compartment liner 58 and the frame 12 against the ingress of air.

At its outer peripheral edge the frame 12 is formed with a rearwardly extending flange 74 and a second flange 76 which lies in a plane parallel to the plane of the web 50 but to the rear thereof, giving a stepped effect to the outer edge.

At its forward edge the outer shell 18 is bent inwardly at 78 and then back upon itself at 80 to form a flange 82 of double thickness of metal. The free edge of the inner thickness of the metal is bent at 84 toward the center of the cabinet to provide a flange 86 parallel to the flange 82 and to the rear thereof. This flange 86 lies against the rear face of the frame flange 76 and is secured thereto by suitable self-tapping screws 87. The flanges 74 and 76 of the frame and the flanges 82 and 86 form, with the shell 18, a

generally rectangular recess or pocket 88 around the outer periphery of the frame 12 and between the frame and the shell.

Within the recess 88 there is positioned a plurality of spring clips 90 which retain the ornamental trim strips 92 in place. The shape of the clip 90 is shown most clearly in Fig. 5 where it is seen to be formed of a single piece of resilient wire. The clip comprises a pivot leg 94, a hook 96 at one end, an elbowed arm 98 connecting the hook 96 and the pivot leg 94, and an anchor 100 which is shaped to have a portion 102 seated against the outer edge of the flange 76 and another and elbowed portion 104 overlying the flange 76. The anchor 100 is connected to the pivot leg 94.

After the outer shell 18 has been secured to the frame 12, a plurality of the clips 90 are placed in the recess 88 within the portion 102 seated against the flange 76 and the hook 96 engaging the edge 80 of the flange 82. With the clips 90 thus held in place liquid Hydrolene or some other suitable sealing compound 106 is poured into the recess and over the anchor 100 of the clips to seal the joint between the frame 12 and the outer shell 18 against leakage of air into the insulated space in the cabinet. While the clips 90 function without any means for holding them in the recess 88, the sealing compound 106 covers their anchors 100 and when hardened prevents accidental or inadvertent removal of the clips.

The ornamental trim strip 92 which may be an aluminum extrusion is sufficiently wide to cover the gap between the web 50 of the frame and the edge 80 of the outer shell flange 82 and to overlie the flange slightly. A pair of hook shaped ribs 105 and 107 are formed on the rear face of the strip 92, the rib 105 being engaged by the hook 96 and the rib 107 engaging the edge 80 of the flange 82. The strip 92 is seated by first engaging the hooks 96 of the clips 90 with the rib 105 and then forcing the strip toward the doorway frame 12 until the rib 107 can engage the edge 80. The elbowed arm 98 of the clip 90 pivots about the leg 94 and may bend itself if necessary to allow the hook 96 to move the distance necessary to seat the strip. However, once the trim strip 92 is in place it is retained by the clip 90 which is under a tension. The strip 92 is readily removed by reversing the operations. In the embodiment illustrated the ornamental trim around the edge of the frame 12 is in five separate pieces with the joints between the pieces at the side and top being covered by flat clips 93 and a name plate 95, respectively.

Fig. 3 is a section taken through the vertical member 42 of the doorway frame 12 adjacent the frost chest or freezing locker 14 and illustrates the manner in which liner 110 forming the freezing locker is secured to flange 112 on the vertical member 42 and cross members 44 and 48. The flange 112 corresponds to the previously described flange 52 and is formed integrally with a second flange 114 which lies in a plane substantially parallel to the plane of the web 50 but spaced to the rear thereof. The flange 114 projects toward the center of the doorway opening of the frost chest 14.

The freezing locker liner 110 is provided at its front with a forwardly facing flange 116 formed integrally with a forwardly projecting and shorter flange 118. A sealing gasket 120 of soft rubber-like material is confined in the space formed by the flanges 116, 118 and 114. An angular metal trim piece 122 substantially covers the flange 114

and the exposed face of the gasket 120 to conceal the joint between the freezing locker liner 110 and the frame 12. A second thermal insulating member 124 having a generally T-shaped cross section is held with the stem 126 of the T between the gasket 120 and the flange 116. The member 124 has a flange 128 positioned between the rearwardly projecting flange of the trim member 122 and the gasket 120; a second flange 130 overlies the liner 110 thereby thermally separating the liner 110 from the angular trim member 122. The joint is secured by a plurality of self-tapping screws 132 which pass through the trim piece 122, flange 114, stem 126 and gasket 120 and screw into the flange 116.

The joint between the freezing locker liner 110 and the frame 12 is of the semi-permanent type because it may be desired at times to remove that portion of the refrigeration system from the cabinet which cools the freezing locker 14. In refrigerators of the type described it is customary permanently to secure the coils of the evaporator to the outer face of the liner, and it is, therefore, expedient and necessary to remove the entire liner from the cabinet rather than to remove the coil from the liner. The removal of the liner from the cabinet 10 is very readily accomplished because it is secured to the frame solely by the screws 132 which are accessible from the front of the cabinet. However, the joint between the freezing locker liner 110 and the frame 12 is efficiently sealed against the ingress of atmospheric air into the insulated space of the cabinet and is ornamenteally concealed by the trim strip 122. It is not necessary that this strip 122 be made continuous around the doorway opening, and it may be made in as many sections or pieces as desired.

Fig. 4 is a cross sectional view taken through the medial cross member 48 to show how the liners 110 and 58 are secured thereto. The joint between the frost chest liner 110 and the medial cross bar 48 is substantially the same as that shown in Fig. 3 and need not be redescribed since the reference characters indicate the similar parts. However, the joint between the food compartment liner 58 and the cross member 48 is changed slightly because this liner is crowned at 134 so that the moisture which is condensed within the food compartment will run down the crowned ceiling to the side walls of the compartment. Since the crowned ceiling 134 is raised above the joint, the liner is formed with a wall 136 which extends downwardly toward a curved wall 138 defining the top of the opening to the liner 58. A sterilizing lamp, not shown in the drawings, may be mounted in the center of the wall 136. The wall 138 is formed integrally with the previously described flange 60 which abuts against the rear edge of the flange 52. The bosses 54 are provided at spaced intervals and include the openings 56. However, it is not possible to use ordinary round head screws at this point since the wall 136 interferes to the application of a screw driver to the screw kerf. The flange 60 is held against the frame at this point, therefore, by a plurality of hex headed self-tapping screws 140. This joint like that previously described is coated with the sealing compound 72 to seal it against leakage of atmospheric air into the insulated space in the refrigerator cabinet.

The cabinet construction at the bottom of the food storage compartment 16 is shown in the enlarged cross-sectional view of Fig. 7. The bottom cross member 46 has the same general cross-

sectional configuration as do the vertical side members 42 and similar reference characters in Figs. 2, 3 and 7 refer to similar parts. The bottom wall of the compartment liner 58 is fastened to the flange 52 of the cross member 46 in the previously described manner.

The top of the machinery compartment 20 is closed by a metallic partition or wall 204 which extends from the front to the rear of the cabinet and across the full width thereof between the side portions of the outer shell 18. The front edge of the wall 204 is spotwelded or otherwise secured to flange 206 of a rail 208 which extends across the front of the cabinet between the side portions of the outer shell 18 and may be secured thereto in any suitable manner. The rail 208 has a vertical front portion 210 integral with the flange 206 and with a second flange 212 which is parallel to the flange 206 and forms the bottom portion of a recess 214 which is similar to the recess 88 at the side of the cabinet. The flange 212 is integral with a vertically extending flange 216 which lies behind the frame flange 76 and corresponds to the flange 86 of the outer shell. The flange 76 of the frame 12 and the flange 216 of the cross rail 208 are secured together by the previously mentioned self-tapping screws 87. The joint between the bottom wall 204 and the rail 210 is sealed by a filling of Hydrolene or some other suitable sealing compound 218 so as to prevent the ingress of atmospheric air into the insulated portion of the cabinet at this point. The wall 204 is closed against the side walls of the outer shell 18 in a conventional and well known manner, and this joint likewise is coated with a sealing compound such as Hydrolene.

The front face 210 of the rail 208 is covered by a double T-shaped member 220 which has its outer face 222 coated with porcelain enamel or other finish so as to match the finish of the remainder of the cabinet. The member 220 is provided with legs 224 and 226 which engage on the outer faces of the flanges 206 and 212, respectively, and if desired may be spotwelded thereto. The member 220 is formed of a single piece of metal and is bent back upon itself to form the legs 224 and 226 so that at its outer edges it comprises edge portions 228 and 230 of double thicknesses of metal. The upper edge 232 of the portion 230 corresponds to the edge 80 of the flange 82 on the outer shell 18 and the ornamental trim strip 92 is engaged between the edge 232 and the hook 96 on the spring clip 90 which is secured in the recess 214 in the same manner as was described in connection with the placing and securing of the spring clips 90 in the recess 88. After the spring clips 90 have been inserted into the recess 214, a suitable sealing compound 106 is poured into this recess to seal the connection between the rail 208 and the frame 12 so that there will be no leakage of atmospheric air into the insulated portion of the cabinet at this point.

The space between the outer shell 18 and the liners 58 and 110 between the liner 58 and the wall 204 and between the liners 58 and 110 is filled with a suitable heat insulating material 142 such as balsa wool which may be placed in the space in any suitable manner. If the insulating material is loose it is blown into place; or it may be formed in blocks or in pads. The freezing locker liner 110 and the food storage compartment liner 58 are thermally separated from each other by the medial cross bar 48 which is an integral part of the frame; there is, therefore, no metal-to-metal contact between these liners

5 where their adjacent edges are secured to the frame 12. The freezing locker 114 is insulated from the food storage compartment 16 by wedge-shaped blocks of insulation 144, and the liner 110 is surrounded by a space 146 for the evaporator tubing which in part is defined by a stiff cardboard-like wrapper 148 and in part by the insulation 144.

10 The main or outer door 32 (Figs. 2 to 5) includes an outer shell 36 and an inner panel 34 with the space between the outer shell 36 and the panel 34 filled with heat insulating material similar to the material 142. The metallic shell 36 has a generally pan-like shape so that there will be substantial thickness to the door. Around its outer periphery the shell 36 has a turned-in flange 150 to which is secured, as by welding, an angle member 152 the wider flange of which is coextensive with the flange 150. The sealing gasket 40 which extends around the outer periphery of the door is of a well-known shape and is provided with a portion 154 confined between the outer peripheral edge of the panel 34 and the shell flange 150 so that the hollow sealing portion 156 is seated against the flange 82 when the door is closed (Figs. 2 and 4). The panel 34 is secured to the shell 36 and the gasket 40 is held in place by a plurality of screws 158 the heads of which are concealed by the sealing portion 156 of the gasket.

15 Opposite the medial cross member 48 a reinforcing channel member 160 is secured across the full width of the door and in the space between the panel 34 and the shell 36. The channel member 160 is bent inwardly at 162 toward the angle member 152 and at its extremities is provided with outwardly extending ears 164 which are spotwelded to the angle member 152 (Fig. 5). The channel 160 and a similar channel 161 (Fig. 2), which preferably is placed somewhat below the latch position indicated by the reference character 166 (Fig. 1), give rigidity to the door and, with the structural angle member 152, prevent the door from buckling or twisting.

20 To give the panel 34 a substantial amount of rigidity it is provided with ribs or ridges 168 and 170. The rib 168, generally rectangular in shape, is formed in the panel 34 opposite the freezing locker 114, and the rib 170, likewise generally rectangular in shape with a crowned portion conforming to the crowned wall 138, lies opposite the edge of the access opening to the moist-cold compartment 16 when the door is closed. The rib construction reduces the space between the frame 12 and the door 32 when the latter is closed (Figs. 2, 3 and 4) and cooperates with the sealing gasket 40 substantially to prevent heat losses in the food storage portion of the cabinet.

25 A generally channel-shaped member 172 is laid against the inner face of the panel 34 between the ribs 168 and 170 and with its open side directed toward the open side of the channel member 160. The channel 172 is secured to the channel 160 by a pair of U-shaped brackets or stirrups 174 which have the base portion 176 thereof welded to the base of the channel 160. The U-shaped brackets are positioned adjacent the extremities of the channel 160 and the legs thereof are provided with the turned-in flange or foot portions 178 which are secured by suitable means such as screws 179 to web 180 of the channel member 172. The legs of the U-shaped bracket 174 are of a length which will hold the web or base 180 of the channel 172 flat against the inner face of the door panel 34.

A flexible vapor seal 182 is secured across the interior of the door immediately below the channels 160 and 172 and divides the interior of the door into an upper compartment 200 and a lower compartment 202. The vapor seal 182 preferably is made of a waterproof tape such as Permacell, and an edge portion 184 thereof is held between the web 180 of the channel 172 and the inner face of the door panel 34, and the other edge 186 is secured to the inner face of the shell 36. The vapor seal 182 is secured to the shell 36 by a coat of bituminous cement 188 and is sealed against the panel 34 by a similar coating of bituminous cement 190, the web 180 being provided with a raised rib 192 along its center so that a quantity of soft permagum may be held therein for sealing purposes. If desired the tape or seal 182 may have an adhesive coating for sticking it to the shell 36 and panel 34.

The panel 34 is secured to the channel 160 by one or more, and preferably four, long screws 194 which also secure a hollow divider gasket 196 across the face of the panel 136 between the ribs 163 and 170 and in such position so that the gasket 196 seals against the cross bar 48 when the door 32 is closed. The divider gasket 196 prevents cold air from circulating from the frost chest 14 to the moist cold storage compartment 16. The long screws 194 are positioned close to the center of the gasket 196 and, therefore, the center of the door so that the pressure with which the gasket 196 seals against the doorway frame 12 may be adjusted. Other and shorter screws 198 secure the gasket to the panel 34 and channel 172 at other spaced points across the door and likewise hold the channel 172 against the inner face of the panel 34. The vapor seal tape 182 is flexible and the portion which extends across the interior of the door is wider than the door is thick so that adjustments may be made in the distance between the panel 34 and the shell 36 to adjust the pressure of the dividing gasket 196 against the frame.

When the refrigerator is operating normally the average temperature differential between the freezing compartment 14 and the storage compartment 16 will be about 30° to 32° F., and consequently, that portion of the panel 34 opposite the freezing locker 14 will be subjected to much colder temperatures than the portion of the panel 34 opposite the storage compartment 16 despite the fact that the freezing compartment may be provided with inner doors 24. This temperature will be substantially below freezing and air trapped in the insulated portion of the door will be substantially cooled. The vapor seal 182 divides the insulated portion of the door into the two compartments 200 and 202 and prevents circulation of air within the insulated space and between the compartments. The cooling effect that the freezing locker has upon the main outer door 32, therefore, is not transmitted to any appreciable extent to the moist-cold compartment 16.

In order that the door 32 illustrated in section in Figs. 2 and 3 will not leak along the peripheral joint between the shell 36 and the inner panel 34, it is necessary that the securing screws 158 be located quite close together. It has been found in practice that large sheets of moldable plastic material such as that from which the panel 34 is made have a tendency to warp and even though they be provided with stiffening ribs 168 and 170, the marginal edges of the door show a tendency to present a wavy or non-⁷⁵

planar edge surface. Consequently, when such a panel is secured to the shell 36 and the reinforcing angle member 152, the attaching or securing screws 158 must be located close together so as to minimize the warping effect.

The marginal edge construction of the door panel and the joint illustrated in Figs. 8 and 9 have been found to provide an airtight joint between the inner panel and the shell by minimizing the warping effect at the edge of the inner panel and by providing an improved sealing gasket which permits use of fewer securing screws.

Door 240 has an inner panel 242 and outer shell 244 which are similar, respectively, to the panel 34 and the shell 36 except as hereinafter noted. The shell 244 has an inturned flange 246 formed around its peripheral edge which is secured as by welding to an angle member 248, the longer flange of the angle being coextensive with the flange 246. The inner panel 242 is formed with an inwardly-projecting (i. e., projecting toward the interior of the door) arcuately shaped bead 250 which extends completely around and is spaced inwardly from the edge of the panel 242 a distance approximately equal to the width of the flange 246.

A sealing gasket 252 is secured around the edge of the door and has two sealing portions, sealing portion 254 being hollow and thereby compressible so that it seals the space between the door 242 and the face of the cabinet. The portion 254 of the gasket 252 engages the flange 82 in the same manner as does the portion 156 of the gasket 40 and for the same purposes. The second sealing portion 256 of the gasket is confined between the marginal edge of the panel 242 and the flange 246 for the purpose of sealing the space between the panel 242 and the shell 244 against the ingress of atmospheric air. This sealing portion 256 may be ribbed as shown in the drawing to increase its sealing characteristics.

Referring particularly now to Fig. 8, it will be seen that the inner edge of the portion 256 is formed with a hollow compressible bead 258 which is confined between the bead 250 of the panel 242 and a bend 260 in the angle 248. Since it is possible carefully to control the shape and position of the bead 250 and the angle 248 in relation one to the other, the space between these two surfaces is such that the bead 258 is compressed when the panel 242 is connected to the shell 244 by means of suitable screws 262. The heads of the screws 262 are covered by the hollow portion 254 of the gasket.

By using this construction it is possible to eliminate approximately one-half of the screws 262 formerly required for keeping the marginal edges of the inner panel tight against the shell 244 and interposed gasket (Fig. 2), and even with this construction there was no guarantee that a substantially airtight seal could be effected. With the construction shown in Figs. 8 and 9 the marginal edges of the panel 242 have less tendency to assume a wavy or warped shape and should there be any waviness to this portion the air which may leak between the edge of the panel 242 and the shell 244 is prevented from passing into the insulated space by the bead 258 of the gasket.

The construction shown in Fig. 9 is similar to that shown in Fig. 8 except that the bead 258 is replaced by a bead 264 which is solid in construction and is held between inner edge 266 of the flange 246 and the bead 250. The bead

264 performs the same function as does the bead 260, but it is not quite as compressible as the hollow bead. The gasket shown in Fig. 8 is preferably made of a natural rubber which may be made with the hollow portions, while that illustrated in Fig. 9 is made of a synthetic rubber.

The space between the shell 244 and the inner panel 242 is filled with heat insulating material 268 and the remaining construction of the door, particularly the cross-reinforcing members, may be the same as that shown and described with reference to Figs. 2 to 5.

From the foregoing description it is apparent that the refrigerator cabinet of this invention is provided with a doorway frame 12 of plastic material which forms a substantial part of the front face of the cabinet, acts as the thermal breaker strip between the outer shell and the liners and between the liners themselves, and carries a substantial part of the load imposed by the liners 118 and 58. This frame 12 is light in weight, and since it has a generally channel shaped cross section is also structurally stable and strong. The joints between the frame and the liners and between the frame and the outer shell of the cabinet are sealed to prevent any leakage of atmospheric air into the insulated space in the cabinet. In order to insure that the cabinet is completely sealed, the other joints which are at the rear and bottom of the cabinet are also sealed in an airtight manner.

The main and outer door of the cabinet is efficient in cooperating with the frame and shell of the cabinet to seal the food compartment liners from the atmosphere and from each other. It also has its insulation containing space sealed in an airtight manner against the ingress of atmospheric air. By virtue of the fact that the door is exteriorly and interiorly divided into portions corresponding to the freezing locker and the moist-cold compartment, there is only a minimum heat transfer between these compartments via the door.

It will be obvious to those skilled in the art that numerous modifications and changes in the cabinet forming the present invention may be made without departing from the spirit and scope thereof which is set out in the appended claims.

What is claimed as new and desired to be secured by United States Letters Patent is:

1. A refrigerator cabinet including a compartment adapted to be refrigerated and an insulated space around the compartment sealed against the atmosphere, comprising in combination, a one-piece molded plastic material doorway frame including a pair of generally vertical members connected by integral cross members, said vertical members and said cross members defining the access opening to the compartment, said members having a substantially rearwardly projecting flange around the access opening, a liner defining the compartment and having a forwardly facing flange around its open side adapted to face said flange on said frame, removable means securing said flanges together to mount said liner to said frame so that it may readily be removed from the cabinet, a sealing gasket coextensive with said flanges and clamped therebetween so as to seal against leakage of air between said flanges and into the insulated space, a trim member ornamenteally covering said sealing gasket and the joint between said flanges, and means thermally insulating said trim member from said liner.

2. A refrigerator cabinet including a compartment adapted to be refrigerated and an insulated space around the compartment sealed against the atmosphere, comprising in combination, a one-piece molded plastic material doorway frame including a pair of generally vertical members connected by integral cross members, an outer metallic one-piece shell forming the outer top and side walls of the cabinet, the forward edge of said shell being bent to form an inwardly directed flange of double thickness of metal at the face of the cabinet and a second flange of a single thickness of metal parallel to said double thickness flange but spaced to the rear thereof, said doorway frame being provided with an attaching flange around its outer periphery which is positioned to overlie said second flange on said shell thereby forming a recess at the joint between said frame and said double thickness shell flange, means securing said frame flange to said second shell flange, means contained in said recess sealing the joint between said frame and said shell against the leakage of air therepast, whereby the insulated space in the cabinet is sealed against the atmosphere, an ornamental trim strip closing said recess, and resilient means having an end embedded in said sealing means and a free end engageable with a part of said trim strip removably to hold the latter in place.

3. A refrigerator cabinet including a compartment adapted to be refrigerated and an insulated space around the compartment sealed against the atmosphere, comprising in combination, a one-piece molded plastic material doorway frame including a pair of generally vertical members connected by integral cross members, an outer metallic one-piece shell forming the outer top and side walls of the cabinet, the forward edge of said shell being bent to form an inwardly directed flange of double thickness of metal at the face of the cabinet and a second flange of a single thickness of metal parallel to said double thickness flange but spaced to the rear thereof, said doorway frame being provided with a rearwardly positioned and outwardly extending outer peripheral flange which is positioned to overlie said second shell flange thereby forming a recess at the joint between said frame and said shell, means securing said frame flange to said second shell flange so that said frame is supported by said shell, means contained in said recess sealing the joint between said frame and said shell against the leakage of air therepast, whereby the insulated space in the cabinet is sealed against the atmosphere, an ornamental trim member concealing the gap between said frame and said double thickness flange, and resilient means held in place by said sealing means for removably holding said trim member in place.

4. A refrigerator cabinet including a compartment adapted to be refrigerated and an insulated space around the compartment sealed against the atmosphere, comprising in combination, a one-piece molded plastic material doorway frame including a pair of generally vertical members connected by integral cross members, an outer metallic one-piece shell forming the outer top and side walls of the cabinet, the forward edge of said shell being bent to form an inwardly directed flange of double thickness of metal at the face of the cabinet and a second flange of a single thickness of metal parallel to said double thickness flange but spaced to the rear thereof, said doorway frame being provided with a rearwardly positioned and outwardly extending outer

peripheral flange which is positioned to overlie said second shell flange thereby forming a recess at the joint between said frame and said shell, means securing said frame flange to said second shell flange, means contained in said recess sealing the joint between said frame and said shell against the leakage of air therewith, whereby the insulated space in the cabinet is sealed against the atmosphere, an ornamental trim member concealing the gap between said frame and said double thickness flange, and a plurality of resilient members removably securing said trim member in place.

5. A refrigerator cabinet including a compartment adapted to be refrigerated and an insulated space around the compartment sealed against the atmosphere, comprising in combination, a one-piece molded plastic material doorway frame including a pair of generally vertical members connected by integral cross members, an outer metallic one-piece shell forming the outer top and side walls of the cabinet, the forward edge of said shell being bent to form an inwardly directed flange of double thickness of metal at the face of the cabinet and a second flange of a single thickness of metal parallel to said double thickness flange but spaced to the rear thereof, said doorway frame being provided with a rearwardly extending outer peripheral flange which is positioned to overlie said second shell flange thereby forming a recess at the joint between said frame and said shell, means securing said frame flange to said second shell flange, means contained in said recess sealing the joint between said frame and said shell against the leakage of air therewith, whereby the insulated space in the cabinet is sealed against the atmosphere, an ornamental trim member concealing the gap between said frame and said double thickness flange, and a plurality of resilient members removably securing said trim member in place, said resilient members being secured in said recess by said sealing means.

6. A refrigerator of the multi-temperature multi-compartment type, including in combination a cabinet containing a plurality of compartments adapted to be refrigerated, heat insulating material in said cabinet insulating said compartments from each other, a single door adapted to close said compartments and having an inner panel of a thermally nonconducting material, an outer shell, and heat insulating material filling the space within said door, sealing gasket means carried by said door to seal said compartments from the atmosphere and from each other when said door is closed, and sealing means within said door to divide the insulated space therein into the same number of dead air spaces as there are refrigerated compartments, said sealing and dividing means being positioned within said door opposite the insulating material between said compartments, whereby circulating air within said door is prevented from effecting heat transfer between said compartments.

7. A refrigerator of the multi-temperature, multi-compartment type, including in combination a cabinet containing a plurality of compartments adapted to be refrigerated, heat insulating material in said cabinet insulating said compartments from each other, a single door adapted to close said compartments and having an inner panel of a thermally nonconducting material, an outer shell, and heat insulating material filling the space within said door, sealing gasket means carried by said door to seal said

compartments from each other to prevent air circulating therebetween when the door is closed, adjustable means carried by said door in the interior thereof whereby the pressure exerted by said sealing gasket means may be adjusted, and sealing means within said door to divide the insulated space therein into the same number of dead air spaces as there are refrigerated compartments, said sealing and dividing means being positioned within said door opposite the insulating material between said compartments, whereby circulating air within said door is prevented from effecting heat transfer between said compartments.

8. A door for a multi-temperature, multi-compartment refrigerator comprising in combination, a one-piece inner panel of a thermally nonconducting material, an outer shell secured around its periphery to said inner panel, heat insulating material filling the space between said panel and said shell, means extending between and sealed to said panel and said shell dividing the door into the same number of compartments as there are compartments within the refrigerator, each door compartment being of substantially the same area size as the access opening to the refrigerator compartment to which it is adapted to be opposite, a sealing gasket secured to the periphery of said panel, and a dividing gasket secured across the face of said panel adjacent said sealing and dividing means with its extremities adjacent said sealing gasket.

9. A refrigerator cabinet for a refrigerator of the multi-temperature multi-compartment type, including in combination an outer shell having a forward edge portion lying in the plane of the cabinet face, a food storage compartment defining liner for each compartment, a doorway frame of molded plastic material having a substantially flat surface lying in the plane of the cabinet face, said doorway frame comprising longitudinal and cross members defining the access openings to the food storage compartments, said outer shell being attached to the outer peripheral edge of said frame and said liners being attached to the longitudinal and transverse members of said frame whereby said frame thermally insulates the forward edges of said liners and said shell from each other, heat insulating material filling the space defined by said shell, said liners and said frame, a single door closing said access openings, peripheral and transverse sealing gasket members carried by said door and adapted when said door is closed to engage against said shell edge portion and said frame to seal each of the food storage compartments from each other and from the atmosphere, said door including a single piece inner panel of plastic material and an outer shell having their marginal edges secured together, the space between said panel and said shell being filled with heat insulating material, and sealing means contained within said door dividing the insulated space into the same number of compartments as there are food storage compartments, said sealing and dividing means being positioned within said door opposite said frame cross bars and adjacent said transverse gasket members thereby to prevent circulation of air within the insulated space in said door from a point opposite one compartment to a point opposite a second compartment, whereby heat transfer between the refrigerated compartments through the door is minimized.

10. A refrigerator cabinet for a refrigerator of

the multi-temperature multi-compartment type, including in combination an outer shell having a forward edge portion lying in the plane of the cabinet face, a compartment defining liner for each of the refrigerated compartments, a doorway frame of molded plastic material having a substantially flat surface lying in the plane of the cabinet face, said doorway frame comprising longitudinal and cross members defining the access openings to the refrigerated compartments, said outer shell being attached to the outer peripheral edge of said frame and said liners being attached to the longitudinal and transverse members of said frame whereby said frame thermally insulates the forward edges of said liners and said shell from each other, heat insulating material filling the space defined by said shell, said liners and said frame, a single door closing said access openings, sealing gasket means carried by said door and adapted to engage against said shell to seal each of the refrigerated compartments from each other and from the atmosphere, said door including a single piece inner panel of plastic material and an outer shell, the space between said panel and said shell being filled with heat insulating material, and means carried by said door whereby the pressure exerted by that portion of said sealing gasket means sealing against that portion of said frame thermally separating said liners from each other may be adjusted.

11. A refrigerator cabinet for a refrigerator of the multi-temperature multi-compartment type, including in combination an outer shell, a compartment defining liner for each of the refrigerated compartments, a doorway frame of molded plastic material having a substantially flat surface lying in the plane of the cabinet face, said doorway frame comprising longitudinal and cross members defining the access openings to the refrigerated compartments, said outer shell being attached to the outer peripheral edge of said frame and said liners being attached to the lon-

5 gitudinal and transverse members of said frame whereby said frame thermally insulates the forward edges of said liners and said shell from each other, heat insulating material filling the space defined by said shell, said liners and said frame, a single door closing said access openings, sealing gasket means carried by said door to seal the refrigerated compartments from the atmosphere, a dividing sealing gasket means carried by said door and adapted to seal against a transverse member to seal adjacent compartments from each other, said door being constructed with a single piece inner panel of plastic material and an outer shell, the space between said panel and said shell being filled with insulating material, structural bracing means secured within said insulated space in said door, and means carried by said door and cooperating with said bracing means whereby the pressure exerted by said divider sealing gasket means against said transverse member may be adjusted.
